SCAFFOLD

William Buckles, South Bend, Ind.

Application May 29, 1942, Serial No. 445,003

7 Claims. (Cl. 304—2)

This invention relates to improvements in scaffolds.

The primary object of the invention is to provide a scaffold which may be assembled and disassembled easily, quickly and level-by-level.

A further object is to provide a scaffold wherein the use of nails may be reduced to a minimum and wherein nails are used primarily for unstressed positioning purposes and for bracing.

A further object is to provide a scaffold wherein simple metal fixtures serve to firmly and positively interconnect the various posts, platform supports, and other wood parts, are readily removable therefrom, and reduce to a minimum the need for bracing members.

A further object is to provide novel means for firmly interconnecting sections of vertical posts positioned to extend one above another in a manner to increase the strength and firmness of the interconnection as the stress exerted thereupon increases.

A further object is to provide a wood scaffold with metal interconnecting and supporting members having bearing surfaces provided with sharp edges which are adapted to increasingly penetrate the wood parts engaged thereby for increased anchorage therewith as the stresses applied to the scaffold increase.

A further object is to provide a wood scaffold with metal parts serving to frictionally grip and interconnect wood parts and provided with sharp edges engaging the parts and biting therein as said parts shift to improve their anchorage with the parts and to increase the friction between the parts as the same are subjected to stresses which tend to shift one relative to another.

Other objects will be apparent from the description, drawings and appended claims.

In the drawings,

Fig. 1 is a view of the scaffold in elevation.

Fig. 2 is an end view of a double post scaffold.

Fig. 3 is an end view of a single post scaffold.

Fig. 4 is an enlarged fragmentary end view of a double post scaffold illustrating the wheeling and pass-up levels and an intermediate hopping plank level.

Fig. 5 is an enlarged fragmentary view illustrating one arrangement for clamping a platform supporting member to a post.

Fig. 6 is an enlarged fragmentary view illustrating an arrangement for interconnecting sections of an upright post.

Fig. 7 is an enlarged plan view of one form of clamp used in Figs. 5 and 6.

Fig. 8 is a sectional view of the clamp taken on line 8—8 of Fig. 7.

Fig. 9 is an enlarged perspective view of a clamp used in Fig. 5.

Fig. 10 is an enlarged fragmentary view illustrating another arrangement for clamping a platform supporting member to a post.

Fig. 11 is an enlarged view of a clamp used in Fig. 10.

Fig. 12 is a sectional view taken on line 12—12 of Fig. 11.

Fig. 13 is a perspective view of a clamp used in Fig. 10.

Fig. 14 is an enlarged fragmentary view illustrating another arrangement for clamping a platform supporting member to a post.

Fig. 15 is an enlarged sectional view of the clamp used in Fig. 14, taken on line 15—15 of Fig. 16.

Fig. 16 is a sectional view of one part of the clamp shown in Fig. 15, taken on line 16—16 of Fig. 15.

Fig. 17 is a face view of the other part of the clamp shown in Fig. 15.

Fig. 18 is an enlarged fragmentary detail view of the bracket used in Fig. 4.

Fig. 19 is a fragmentary perspective view of a wheeling level supporting member.

Fig. 20 is a perspective view of a hopping level supporting member.

Referring to the drawings, which illustrate the preferred embodiment of the invention, the numeral 21 designates vertical wood posts. These posts are each supported by mud pads or bearing members 22.

Where the required height of the post exceeds the length of available post sections, the sections may be spliced as illustrated in Fig. 6. For this purpose a clamp, as best illustrated in Figs. 15—17 is secured to the lower section spaced below the upper end thereof. This clamp includes an angle iron having a horizontal leg 23 and a vertical leg 24. The angle iron is of a length in the order of 8 inches. The leg 24 is provided with bolt receiving apertures adjacent each end and with a plurality of sharp weld spots or spurs 25 positioned between the bolt holes. The other part of the clamp constitutes a U-shaped steel plate having a base 26 parallel opposed legs 27 and out-turned aligned flanges 28. The U-shaped clamp part is of a size to fit snugly around the post, such as a 4 x 4, with the legs 27 preferably slightly shorter than 4 inches, whereby the outer faces of flanges 28 preferably extend inwardly

55 from the face of the post against which leg 24

40 is secured to the lower section spaced below the upper end thereof. This clamp includes an angle iron having a horizontal leg 23 and a vertical leg 24. The angle iron is of a length in the order of 8 inches. The leg 24 is provided with bolt receiving apertures adjacent each end and with a plurality of sharp weld spots or spurs 25 positioned between the bolt holes. The other part of the clamp constitutes a U-shaped steel plate having a base 26 parallel opposed legs 27 and out-turned aligned flanges 28. The U-shaped clamp part is of a size to fit snugly around the post, such as a 4 x 4, with the legs 27 preferably slightly shorter than 4 inches, whereby the outer faces of flanges 28 preferably extend inwardly

of the angle iron bears. The inner face of the base 26 is provided with a plurality of sharp weld spots or spurs 29. The flanges 28 are provided with apertures registering with the apertures in leg 24 to receive bolts 30 by means of which the parts are clamped together around the post. As the nuts 31 on bolts 30 are drawn tight, the weld spots 25 and 29 are forced into the post, and thus the clamp is firmly anchored in desired position on the post.

The upper post section to be spliced to the lower post section mounting the clamp described above is then positioned with its lower end bearing on horizontal leg 23 of the angle iron, and a pair of clamps 32, best illustrated in Figs. 7 and 8, are used to connect the sections. The clamps 32 are formed of a metal bar bent to rectangular shape, with its ends welded together. The width of the opening in clamp 32 is substantially equal to the thickness of a single post 21, and the length of said opening is slightly greater than the combined thicknesses of two juxtaposed post sections. The inner edges of opposite ends of clamp 32 are sharp and rough at 33. Clamps 32 encircle the ends of the post sections to be spliced and are driven to inclined position to bring their opposite horizontal sharp end edges in biting engagement with the post sections. A nail 34 is driven into one post section to support the upper end of each clamp, and a nail 35 is driven into the opposite face of the other post section above the lower end of each clamp, as illustrated in Fig. 6. The nails hold the clamp until initial reaction to application of stress occurs. The use of two clamps, firmly applied to the posts and spaced apart as shown, serves to securely splice the post sections. The application of stress to the resultant post assembly serves to cause the edges 33 of the clamps to bite into the posts deeper and thus increase the splicing and clamping effect or action of the clamps.

Horizontal members to support planks at various working levels are secured to the posts 21 at desired levels. Thus, referring to Fig. 3, which illustrates a double pole scaffold, members 36 support planks at wheeling levels, members 37 support planks at pass-up levels, and members 38 support hopping planks. The platform supporting members are preferably of the construction illustrated in Fig. 19, which shows wheeling level supporting member 36. Two or more blocks 39 are secured to the supporting member 36 in pairs spaced apart a distance equal to the thickness of posts 21. Each block 39 has a central cut-out 40 formed in one edge thereof extending transversely of the member 36 and an aperture 41 is formed in the member 36 in substantially centered relation to each cut-out 40.

One form of interconnection between platform supporting member and post is illustrated in Fig. 5. A wedge block 42 having a lower inclined outer surface 43 is placed at desired elevation on post 21, and a clamp 32 is employed to secure the block to the post by means of securing members 44, such as nails or staples, as explained above. Member 36 is then positioned upon the upper end of block 42 in engagement with post 21. Blocks 39 are positioned at opposite sides of post 21 to prevent lengthwise movement of the member 36. An anchor clamp, best illustrated in Fig. 9, is employed to anchor the member 36 to the post. The anchor clamp is formed from a metal bar bent in substantially U-shape to provide a base 45 of a length slightly greater than the thickness of post 21, a pair of opposed parallel arms 46, and a pair 75

of downturned parallel terminal arms 47 each having sharpened lower inner edges 48. The anchor clamp is positioned with its base 45 bearing against the side of post 21 opposite that engaged by the putlogs, its arms 46 alongside opposite faces of post 21 and above member 36, and its terminal arms 47 alongside the outer face of member 36 so that their edges 48 may bite into said member. It will be observed that clamp 32 holds the block 42 and the member 36 positively at desired elevation, blocks 39 hold said member against longitudinal sliding movement relative to the post, and the anchor clamp prevents lateral separation of said member from the post. The blocks 39 and the anchor clamp also serve to hold the member 36 perpendicular to the post. Planks 49 are supported by adjacent members.

Another arrangement for supporting a platform supporting member on a post is illustrated in Fig. 10. This construction utilizes a post clamp of the construction illustrated in Figs. 11 and 12 which is formed from a steel sheet bent to form an upper inclined portion 50, a horizontal shoulder portion 51 and a lower inclined bearing portion 52 substantially perpendicular to portion 50 and of substantially triangular form terminating in a reduced lower end having a sharpened edge 53. A nail hole 54 is formed in portion 52 spaced slightly above edge 53. Upper inclined portion 50 has a rectangular opening 55 formed therein to fit snugly around post 21 when shoulder portion 51 is positioned horizontally, said opening extending to the line of bend between portions 50 and 51, as illustrated in Fig. 12. The post clamp is positioned at desired elevation on the post, and nails 55' are driven into the post at nail hole 54 and opening 55 to initially position the clamp on the post. Thereafter, as stress is exerted upon the clamp, edge 53 bites into the wood and the upper edge of opening 55 engages the post more firmly, to increase the purchase of the clamp on the post. Platform supporting member 36 is supported on clamp shoulder 51, with blocks 39 engaging opposite faces of post 21. An anchor clamp 56, illustrated in Fig. 13, is passed through the aperture 41 in member 36 and engaged with post 21. Anchor clamp 56 has an elongated shank including a screw threaded end portion 57 and a rigid perpendicular arm 58 at its opposite end whose inner terminal edge is sharpened at 59. Arm 58 bears against post 21 and the shank of the clamp extends alongside the post and through aperture 41 of member 36. A nut 60 is threaded on the end of the shank and cooperates with a lock washer to lock the parts.

Another method for securing a platform supporting member to a post is illustrated in Fig. 14. A clamp as illustrated in Fig. 15, and comprising angle iron 23-24 and U-plate 26-28, secured together by bolts 30, is clamped upon post 21. Platform supporting member 36 is supported on the angle iron at angle leg 23. An anchor clamp 56 serves to secure the member 36 to the post.

It will be understood that the combination of the clamps for supporting and anchoring the platform supporting members to the post is illustrative only, and that the respective supporting and anchoring clamps may also be used in other combinations.

Referring to Figs. 2 and 4, it will be observed that wheeling platform supporting member 36 is provided with two spaced pairs of blocks 39 which fit around spaced posts in a double post scaffold, and which cooperate with suitable clamps to secure opposed ends of the member

36. Pass-up platform supporting member 37 is of shorter length than wheeling platform supporting member 36, and the blocks 39 thereof are preferably positioned adjacent one end thereof. This necessitates the use of a brace 61 of the construction best illustrated in Figs. 4 and 18 to support the elongated projecting portion of the member 37. Brace 61 is formed from a metal bar or pipe having an angularly bent upper end portion 62 and an angularly bent lower portion 63 extending substantially perpendicular to portion 62. A sharp metal spur 64 projects from the upper end of portion 63. The outer end of member 37 is preferably provided with a U-shaped metal reinforcing sheath 65. Upper brace portion 62 is bolted at 66 to the outer sheathed end of member 37. Lower portion 63 of brace 61 has a nail-receiving opening whereby a nail 67 may position said portion 63 against post 21 so that spur 64 will impale said post to improve the anchorage of the brace to the post as the tilting stress applied to member 37 increases. The hopping level platform supporting member 38 is of short length, and hence the anchorage thereof with the post 21 by means of a U-clamp element, as shown in Fig. 16, will generally be sufficiently firm and solid to render additional support or bracing thereof unnecessary. Member 38 is preferably formed from an angle iron as illustrated in Fig. 20 and its horizontal leg is preferably provided with a plurality of sharp weld points or spurs 68 for impaling planks 49 placed thereon, which permits use of the member 38 as a narrow scaffold level which may be raised to any desired height.

In erecting the scaffold, the individual posts are erected and suitably braced until the first level has been erected. Thereafter, cross-braces 69 may be secured at the ends of the scaffold and about three or four bays apart in long scaffolds, and ribbon braces 70 between the cross-braced posts will be ample in a double post scaffold in view of the effective bracing obtained from the wheeling platform supporting members 36. In single post scaffolds, the same cross and ribbon braces may be used, and the top and center of each post may be secured to the structure by tie braces 71. If the scaffold is erected in advance of the structure, the posts may then be anchored to the ground by braces 72.

It will be observed from the above the scaffold utilizes a few metal fixtures which solidly anchor and secure the parts, and only a few nails are required for positioning purposes. The fixtures are essentially clamps which take the full stress exerted upon the nails which are merely driven to hold the parts in position until the stress reaction occurs. The fixtures are readily applied in assembling the scaffold, relocated level-by-level, and disconnected or removed in wrecking the scaffold. All of these fixtures act with a combined clamping and impaling effect, and take stresses in a manner to increase their clamping and impaling action as applied stresses increase.

The limitation in the use of nails facilitates speedy erection, relocation of platform levels, and wrecking, and the positioning function of the nails avoids necessity of driving them completely into the wood, so their stripping or removal in wrecking is simple and easily accomplished. Also, it will be noted that after wrecking, the various wood parts will be substantially clean and free from nails, etc., so that their re-use in a new scaffold is possible without extensive stripping.

Attention is directed to the fact that the combination and relation of the parts as above described eliminates the use of so-called ledgers or ribbons which are conventionally securely nailed to the scaffold posts at each level and which extend completely around the building for the purpose of supporting conventional putlogs.

While the use of the platform supporting members has been illustrated and described only for plank supporting purposes, they may also be used as derrick arms and the like by use of the same clamps and cooperating parts discussed above.

I claim:

1. A scaffold clamp for supporting a horizontal member on a post, comprising a U-shaped member having laterally outwardly bent end portions, an angle iron, draw bolts connecting said angle iron and end portions in post embracing relation, a portion of said angle iron projecting horizontally outwardly from said post, and post engaging projections on the post engaging faces of said member and angle iron.

2. In a scaffold including an upright post and a horizontal member carried by said post intermediate the height thereof, a U-shaped member having laterally outwardly bent end portions, an angle iron, draw bolts connecting said angle iron and end portions in post embracing relation with a portion of said angle iron projecting horizontally outwardly from said post to support said horizontal member, post engaging projections on the faces of said U-shaped member and angle iron which engage said post, and a clamp spaced vertically from said angle iron and releasably anchoring said horizontal member to said post.

3. In a scaffold including an upright post and a horizontal member carried by said post intermediate the height thereof, a U-shaped member having laterally outwardly bent end portions, an angle iron, draw bolts connecting said angle iron and end portions in post embracing relation with a portion of said angle iron projecting horizontally outwardly from said post to support said horizontal member, post engaging projections in the inner faces of said angle iron and U-shaped member, and a clamp adjustably carried by said horizontal member and having a horizontal shank extending alongside said upright and a perpendicularly bent end portion engaging the surface of the post opposite that engaged by said horizontal member.

4. In a scaffold including an upright post and a horizontal member carried by said post intermediate the height thereof, a U-shaped member having laterally outwardly bent end portions, an angle iron, draw bolts connecting said angle iron and end portions in post embracing relation with a portion of said angle iron projecting horizontally outwardly from said post to support said horizontal member, post engaging projections on the inner faces of said angle iron and U-shaped member, an L-shaped clamp extending through said horizontal member to releasably anchor said horizontal member to said post, and means for drawing up said clamp.

5. In a scaffold including an upright post and a horizontal member carried by said post intermediate the height thereof, a U-shaped member having laterally outwardly bent end portions, an angle iron, draw bolts connecting said angle iron and end portions in post embracing relation with a portion of said angle iron projecting horizontally outwardly from said post to

support said horizontal member, post engaging projections on the inner faces of said angle iron and U-shaped member, a pair of blocks secured to said horizontal member and positioned alongside opposite faces of said post, and a releasable clamp anchoring said member to said post in spaced relation above said angle iron.

6. In a scaffold including an upright post and a horizontal member carried by said post intermediate the height thereof, a U-shaped member having laterally outwardly bent end portions, an angle iron, draw bolts connecting said angle iron and end portion in clamping relation on said post, a portion of said angle iron projecting horizontally outwardly from said post to support said horizontal member, post engaging projections on the inner faces of said angle iron and U-shaped member, a pair of blocks secured to said horizontal member and positioned alongside opposite faces of said post, one of said blocks having a notch in its inner face reg-

istering with a passage in said horizontal member, and a releasable L-shaped clamp having a shank mounted in said notch and passage and an end portion anchored at said post.

5. 7. In a scaffold including an upright post and a horizontal member carried by said post intermediate the height thereof, a U-shaped member having laterally outwardly bent end portions, an angle iron, draw bolts connecting said angle iron and end portion in clamping relation to said post, a portion of said angle iron projecting horizontally outwardly from said post to support said horizontal member, post engaging projections on the inner faces of said angle iron and U-shaped member, a releasable clamp spaced vertically from said angle iron and anchoring said horizontal member to said post, and a diagonal brace carried by and projecting downwardly from said horizontal member and having a sharp spur at its lower end adapted to pierce said post.

WILLIAM BUCKLES.
